UNITED STATES PATENT OFFICE.

DAVID CHARLES FEATHER, OF DENVER, COLORADO, ASSIGNOR TO THE FEATHER MOTOR APPLIANCE COMPANY, OF DENVER, COLORADO, A CORPORATION OF COLORADO.

SPRING COMPRESSOR.

Application filed May 17, 1926. Serial No. 109,663.

My invention relates to compression tools of the type used on engines of motor vehicles for the removal of valves by releasing them from the pressure of their springs, and commonly known as "valve lifters." It is an object of the present invention to provide a tool of the above described type, which in connection with interchangeable and removable jaws, has a simple mechanism to lock the same in their operative relation to the lever-members of the tools without bolts, screws or other similar fastening means. Another object of the invention is to lock and unlock the jaws by simple adjustment of a ratchet-bar provided in connection with the lever-members of the tool for locking the latter against retrograde motion when closed together for the compression of a spring or other object engaged by the jaws. A further object resides in constructing the locking device so that it is readily released to return the tool to its open condition and still other objects reside in features of construction and a novel arrangement of parts as are fully set forth in the following detailed description of the invention.

An embodiment of the invention has been illustrated in the accompanying drawings in the several views of which like parts are similarly designated and in which,

Figure 1 represents a sectional elevation of the tool in its open position;

Figure 2, a section along the line 2—2 Figure 1, drawn to an enlarged scale;

Figure 3, a similar section taken on the line 3—3 Figure 1;

Figure 4, a fragmentary top-view of one of the jaws of the tool looking in the direction of the arrow A in Figure 1;

Figure 5, an enlarged perspective view of one of the removable jaw-members of the tool;

Figure 6, a fragmentary sectional view of the tool showing its jaws in closed position;

Figure 7, a similar view of the tool equipped with crossed jaws of different construction which are moved apart when the lever handles of the tool are closed together;

Figure 8, a fragmentary elevation of the tool shown in Figures 1 and 6 showing its application for the removal of a valve of an internal combustion engine; and,

Figure 9, a section on the line 9—9 Figure 1;

Figure 10, a fragmentary elevation of one of the lever-members of the tool without the jaw, looking in the direction of the arrow B in Figure 6.

Referring further to the drawings, the tool comprises two crossed levers 5 pivoted together as at 6, to provide handles 7 and jaw-arms 8. The levers are of channel-section, one passing through a slot of the other, and the jaw-arms have at their extremities outwardly projecting lugs 9 for their pivotal connection in notches 10 of slide-pieces 12 which cooperate with links 13 for the support and connection of the jaws of the tool. The links above referred to are of channel-section and pivoted at their rear extremities to the handles of the levers by screw-pins 14. Their opposite end-portions are provided with inturned flanges 15 to form guide ways for the slide-pieces on the respective jaw-arms.

The slide-pieces which are likewise of channel-section, have parallel side-flanges 16 which fit slidably in the guide ways of the links. The notches 10 cooperating with the lugs of the jaw-arms for the pivotal connection of the parts, are formed at the forward ends of the flanges 16 and the body portions of the slide-pieces engaging with the inner surfaces of the links, have central slots 17 which terminate in enlargements 18 at the forward end of the pieces and which register with transverse slots 19 in the respective links, corresponding in size with the enlargements.

The jaw-members of the tool each consists of a flanged blade 20 of channel-section bifurcated at one end to straddle a valve stem or other similar part of an engine to which the tool is applied, and having at its opposite end, a headed button 21 bent at right angles to enter the slots of the links and slide-pieces on the jaw-arms of the levers. The flanges 22 of the jaw-members have inwardly projecting bosses 23 which by engagement in correspondingly formed notches 24 at the forward ends of the links, determine the position of the jaw-members with relation thereto and cooperate with the headed buttons to hold the members against relative displacement. In the operative

position of the jaw-members, they straddle the end-portions of the respective links, their inturned bosses engage in the notches 24 of the links and the shanks of their buttons extend loosely through the aligned slots of the links and the slide-pieces while the heads of the buttons engage the slide-pieces at opposite sides of their slots. It will be observed that the jaws are thus firmly locked in connection with the links and that they can be detached only after the enlargements of the slots in the slide-pieces have been brought in register with the corresponding transverse slots of the links to permit of the passage of the heads on the buttons of the jaws. Pivoted on one of the lever members, preferably by means of the pivot pin 14 of one of the links, is a curved locking bar 25, which loosely projects through a longitudinal slot 26 of the other lever. The locking bar has at its inner curved edge, a series of ratchet teeth 27 adapted to engage with the slotted lever at the forward end of the slot through which the bar extends, to lock the two levers in their adjusted positions. A coiled spring 28 connecting the bar with the other lever at a rearward point thereof tends to maintain the bar in its normal position in which it engages at the rearward end of the slot 26 as indicated in Figure 6.

A cross pin 29 at the free end of the ratchet bar engaging in notched seats 30 in the edges of the slot 26 limits the opening movement of the lever handles when the bar is in its normal position and a heel 31 at the opposite end of the bar provides a thumb piece for the movement of the bar from its normal position toward the opposite end of the slot against the resistance of the spring 28.

A spring 32 coiled around the pivot of the levers 7 in engagement with the latter, functions to return the levers to their normal open position, after they have been closed together by pressure upon their handles in the operation of the tool.

When the tool is in its normal open position, the cross pin at the free end of the locking bar, rests in the notches of the slot 26 and the enlargement of the slots in the slide-pieces 12 are out of alignment with the transverse slots 19 in the links 13. The jaws 20 are thus locked in rigid connection with the links by the engagement of their bosses 23 in the notches 24 at the ends of the links and by the engagement of their headed buttons at opposite sides of the slots 12 of the slide-pieces.

In order to compress an object such as the valve-springs 34 shown in Figure 8, the lever-arms 7 are pressed together with the result that the locking bar is released from the notches 30. After the spring has been compressed to the desired extent by the engagement of the jaws at opposite ends there-

of, as indicated in Figure 8, the arm 25 is moved about its pivot by pressure on the heel 31 to cause its ratchet teeth 27 to engage with the end of the slot 26. The spring 32 obviously holds the bar in its adjusted position so that the tool may be removed with the valve-spring held firmly between its jaws. To subsequently release the valve-spring, it is but necessary to press the handle 7 of the tool slightly together when the spring 28 will compel the ratchet bar to disengage the forward end of the slot and return to its original position at the opposite end of the same.

The levers of the tool are now free to spread apart until their movement is arrested by the return of the cross pin 29 at the end of the ratchet bar in the seats 30 of the slot 26. To detach the jaw-members 20, the levers are pressed together to release the cross pin 29 from the notches, and the lever arm is then moved forwardly to cause the cross-pin to engage with the surface of the lever arm in which the slot 26 is formed, at opposite sides of the slot as illustrated in Figure 1. The spring 32 again holds the bar in its adjusted position in which it engages the forward end of the slot and in this position of the tool, the levers are brought together a distance sufficient to move the transverse slots of the links to register with the corresponding enlargements of the slots in the slide-pieces. The buttons at the ends of the jaws are now free to pass through the aligned slots and the jaws may be removed by turning their bosses in the notches at the ends of the links until the buttons are free. It is obvious that the jaws may be replaced in a similar manner. Jaws of different construction may be attached to the levers of the tool by the same means, as indicated in Figure 7 of the drawings, showing two jaws 35 and 36 crossed by projecting a shank 37 on one through a slot of the other. The tool in this form will separate its jaws by pressure exerted on its handles for the compression of a spring by engagement with a relatively stationary abutment.

The handles of the tool are slightly curved in one direction as shown in Figure 1 and this taken together with the fact that the jaws 35 and 36 are interchangeable either with each other or with jaws of different form, adapts the tool for use for the compression of springs under different conditions, particularly with reference to the many varying arrangements of parts found in engines of different makes and types.

It will be observed that the jaws are held in place without bolts, screws or other similar fastening means, that they may be instantly removed or replaced by the simple expedient of a slight pressure upon the handles of the tool and adjustment of the locking bar, and that the latter performs in

addition to this distinctive function, the functions of determining the extent of the opening movement of the levers and of locking the levers in any of a plurality of closed 5 positions.

In case, in the use of crossed jaws of the character shown in Figure 7, it is inconvenient to bring the buttons on both of them in register with the slots of the links and 10 slide-pieces, the head of the button of one of the jaws may be eliminated and the jaw fastened in place by means of a set-screw shown at 38.

Having thus described my invention what 15 I claim and desire to secure by Letters Patent is:

1. A tool of the character described comprising crossed levers, a spring to yieldingly resist their operative movement, a slide-piece on an arm of one of the levers and having a slot ending in a wider opening, a link pivoted on the other lever and having a slot alined with the other slot, a jaw-member on the link, having a headed button extending through the slots, and a locking device adapted to hold the levers in an adjusted position in which the slot of the link registers with the opening of the slide-piece 20 to provide a passage for the head of the button.

2. A tool of the character described comprising crossed levers, a spring to yieldingly resist their operative movement, a slide-piece on an arm of one of the levers and having a slot ending in a wider opening, a link pivoted on the other lever and having a slot alined with the other slot, a jaw-member interlocked with the link at an end thereof and having a headed button extending 25 through the slots, and a locking device adapted to hold the levers in an adjusted position in which the slot of the link registers with the opening of the slide-piece to provide a passage for the head of the button.

3. A tool of the character described comprising crossed levers, a spring to yieldingly resist their operative movement, a slide-piece on an arm of one of the levers and having a slot ending in a wider opening, a link pivoted on the other lever and having a slot alined with the other slot, a jaw-member having bosses in interlocking engagement with the link, and provided with a headed button extending through the slots, and a locking device adapted to hold the levers in an adjusted position in which the slot of the link registers with the opening of the slide-piece 30 to provide a passage for the head of the button.

4. A tool of the character described comprising crossed levers, a spring to yieldingly resist their operative movement, a slide-piece on an arm of one of the levers and having a slot ending in a wider opening, a link pivoted 35 on the other lever, provided with a

guideway for the slide-piece and having a slot alined with the other slot, a jaw-member on the link, having a headed button extending through the slots, and a locking device adapted to hold the levers in an adjusted position in which the slot of the link registers with the opening of the slide-piece 40 to provide a passage for the head of the button.

5. A tool of the character described comprising crossed levers, a spring to yieldingly resist their operative movement, a slide-piece on an arm of one of the levers and having a slot ending in a wider opening, a link pivoted on the other lever and having a slot alined with the other slot, a jaw-member on the link, having a headed button extending through the slots, and a locking device adapted to hold the levers in any of a plurality of predetermined relative 45 positions in one of which the slot of the link registers with the opening of the slide-piece to provide a passage for the head of the button.

6. A tool of the character described comprising crossed levers, a spring to yieldingly resist their operative movement, a slide-piece on an arm of one of the levers and having a slot ending in a wider opening, a link pivoted on the other lever and having a slot alined with the other slot, a jaw-member on the link, having a headed button extending through the slots, and a locking device adapted to hold the levers in two adjusted positions for the operation of the tool 50 and in a third position in which the slot of the link registers with the opening of the slide-piece to provide a passage for the head of the button in the application or removal 55 of the jaw.

7. A tool of the character described comprising crossed levers, a spring to yieldingly resist their operative movement, a jaw supported by an arm of one lever, lock-mechanism for the jaw, controlled by the levers, to release the same in a determinate adjusted position of the levers, and a locking device adapted for adjustment to determine said 60 adjusted position of the levers.

8. A tool of the character described comprising crossed levers, a spring to yieldingly resist their operative movement, a jaw supported by an arm of one lever, lock-mechanism for the jaw controlled by the levers, to release the same in a determinate adjusted 65 position of the levers, and a locking device adapted for adjustment to hold the levers in any of a plurality of predetermined positions, inclusive of the adjusted position in which the jaw is released.

9. A tool of the character described comprising crossed levers, a spring to yieldingly resist their operative movement, jaws supported on corresponding arms of the lever, lock mechanism for the jaws controlled by 70

the levers, to release the same in a determinate adjusted position of the levers, and a locking device adapted for adjustment to determine said adjusted position of the levers.

10. A tool of the character described comprising crossed levers, a spring to yieldingly resist their operative movement, a jaw supported by an arm of one lever, lock-mechanism for the jaw controlled by the levers, to release the same in a determinate adjusted position of the levers, and a spring-controlled toothed bar pivoted on one lever and cooperating with the other lever to hold the levers in any of a plurality of predetermined positions inclusive of the adjusted position in which the jaw is released.

11. A tool of the character described comprising crossed levers, a spring to yieldingly resist their operative movement, a jaw supported by an arm of one lever, lock-mechanism for the jaw controlled by the levers to release the same in a determinate adjusted position of the levers, one of the levers having a slot notched at one end, and a spring-controlled locking bar pivoted on the other lever and projecting through the slot, the

bar having at its free end a pin adapted to engage in the notch of the slot, or to engage with the slotted lever outside the notch to hold the levers in their said adjusted position.

12. A tool of the character described comprising crossed levers, a spring to yieldingly resist their operative movement, a jaw supported by an arm of one lever, lock-mechanism for the jaw controlled by the levers, to release the same in a determinate adjusted position of the levers, one of the levers having a slot notched at one end, and a spring-controlled locking bar pivoted on the other lever and projecting through the slot, the bar having at its free end a pin adapted to engage in the notch of the slot, or to engage with the slotted lever outside the notch to hold the levers in their said adjusted position. 35
